ATTORNEY.

UNITED STATES PATENT OFFICE.

DAVID H. FINBERG, OF ST. LOUIS, MISSOURI.

SHOE-HEEL.

1,335,371.

Specification of Letters Patent. Patented Mar. 30, 1920.

Application filed October 25, 1919. Serial No. 333,207.

To all whom it may concern:

Be it known that I, DAVID H. FINBERG, a citizen of the United States, residing at St. Louis, State of Missouri, have invented 5 certain new and useful Improvements in Shoe-Heels, of which the following is a full, clear, and exact description, reference being had to the accompanying drawings, forming a part hereof.

10 The present invention is an improvement on the construction of shoe-heel forming the subject matter of my U. S. Letters Patent numbered 1,296,939, bearing date March 11, 1919, the object of the improvement being to dispense with the brads or nails employed in the patented structure for securing the lift to the plug confined in the bottom socket of the heel. In the present embodiment of my invention the plug inserted 15 in the socket and the lift engaging the tread of the heel are formed of an integral piece of vulcanized rubber (or other material), a suitable stiffening plate, preferably of metal, and directly bearing against the tread 20 of the heel, being embedded in the rubber, the stiffness of said plate preventing the lift from curling or bending away from the heel, all as will herein more fully appear from the following detailed description of 25 the invention in connection with the accompanying drawings in which—

Figure 1 represents a side elevation of a lady's shoe showing the invention applied thereto; Fig. 2 is a vertical middle longitudinal section through the heel; Fig. 3 is a rear elevation with parts in section; Fig. 4 is a cross-section on the line 4—4 of Fig. 2, with a portion of the plug removed; Fig. 5 is a bottom plan of the stiffening plate detached; Fig. 6 is a vertical longitudinal section on the line 6—6 of Fig. 5; Fig. 7 is a side view of the plate; Fig. 8 is a top plan of the stiffening plate detached; Fig. 9 is a top plan of the attachment comprising the lift, the plug, and the stiffening plate; Fig. 10 is a front elevation thereof; and Fig. 11 is a bottom plan of the heel.

Referring to the drawings, S. represents the upper of a conventional shoe for women, 50 C. the counter of the shoe, and H, the heel. Like in my patent aforesaid, the heel in the present embodiment of my invention, is hollow, being cast as a metallic shell of aluminum or equivalent light material, the bottom or tread of the heel being provided 55 with a socket 1 with inwardly and upwardly

converging walls *w* and a substantially flat roof. The said socket receives a plug 2 with which is integrally cast or molded the lift 3, a stiffening plate 4 being embedded in the material (preferably vulcanized rubber), entering into the composition of said plug and lift. In practice, the plate 4 has punched therefrom at points following the bottom boundaries of the plug 2 suitable 65 downwardly projecting prongs *a* which when the rubber is cast or molded around the plate become embedded in the rubber portion forming the lift (Fig. 3), a suitable number of prongs or lips *a'* being punched 70 upwardly or in the opposite direction, the position of said prongs *a'* being such that they bear (with their inner faces) against the sloping walls *w'* of the plug 2, at three points, to wit, one prong at the middle of 75 the rear portion of the wall of the plug and one engaging each end of the breast wall of the plug (Figs. 2, 4, 9; 10); said prongs *a'* likewise engaging the corresponding walls *w* of the socket 1 of the heel (Fig. 2). 80 In other words, when the plug 2 is inserted into the socket 1, the prongs or lips *a'* become wedged between the walls *w* of the socket and the corresponding wall *w'* of the plug, and thereby hold the plate 4 in 85 firm engagement with the tread of the heel. The punching and bending of the prongs *a, a'* from the body of the plate 4 as indicated necessarily results in the formation of holes or openings *o* through which the 90 rubber is free to flow during the molding of the lift and plug, the portions or narrow necks *n* of rubber traversing said openings serving to effect an integral union between the plug 2 and lift 3. In the present embodiment of my invention the plate 4 is 95 formed with a central perforated socket *t* for receiving the head of the screw 5 by which the plug (and lift) is secured to the roof of the socket 1 in pretty much the same 100 manner as in my patent aforesaid, the outer face of the head coming flush with the bottom face of the plate when the screw is fully driven home. To accommodate the screw, 105 the lift is formed with an outwardly tapering central opening or hole *h* the walls of which yield as the head of the screw forces its way through the lift with the driving of the screw into the heel, the walls of the hole subsequently (that is, after the head of the 110 screw has been driven into the socket *t*) expanding to their normal position and leav-

ing the tapered terminal of the hole exposed to the tread of the lift. Eventually of course the hole fills with dirt, but that is quite immaterial as it in no wise detracts 5 from the finish of the heel. The width of the openings α is such that the openings extend partly inside and partly outside of the line of intersection of the outer boundaries of the plug with the lift (Fig. 4) causing 10 portions of the necks n of rubber flowing through the openings to appear beyond and adjacent to the bottom edge of the plug (Fig. 9). These portions simply distribute themselves flush with the upper face of the 15 stiffening plate 4, permitting said face to be brought into direct engagement with the tread of the heel.

It will be seen from the foregoing that the members 2, 3, and 4, constitute a unit 20 or single attachment which may be applied to the heel H by the mere insertion of the plug portion 2 into the socket 1, and securing the attachment by means of the screw 5. The lips a' bearing as they do against 25 the walls of the socket, hold the stiffener plate 4 against outward bending or curling in the event of the heel striking an obstruction or for other reasons, the stiffness of the plate contributing to maintain the lift in 30 permanent contact with the tread of the heel, this construction entirely dispensing with the securing nails of my patent aforesaid.

It is obvious of course that the forms of 35 the lips or burs a, a' , punched from the plate, and the holes resulting therefrom may be changed, any equivalent method of causing an integral union between the plug and lift members of the heel, and the necessary anchoring of the stiffener plate to these 40 members, falling within the scope, and coming within the spirit of my invention. I need not of course limit myself to the precise materials of which the attachment is 45 composed, any equivalent or suitable unitary attachment being contemplated by the invention. However, I do not wish to be understood as excluding attachments composed of separable pieces or sections so long 50 as when assembled, they function in the manner of the present attachment. In the form of the invention as shown, it will be observed that the stiffener plate 4 is disposed along the upper face of the portion 55 of the lift extending beyond the plug 2, the outer portions of the plate bearing directly against the bottom of the heel. It would however be fully within the scope of my invention were the outer portions of the 60 stiffener plate covered over by the rubber entering into the composition of the lift. The preferred construction of course is the one heré shown, it being desirable that the plate form a separating member between 65 the metal heel and the rubber lift. Features

shown but not alluded to are well known in the art and require no description in the present connection.

Having described my invention what I claim is:

1. In combination with a heel provided with a socket leading from the tread of the heel, a lift for the heel, a plug coupled to the lift and secured in the socket, a stiffener member interposed between the lift and tread, and means on the stiffener member 75 engaging the walls of the socket to prevent outward bending of the stiffener.

2. In combination with a heel provided with a socket leading from the tread of the heel, a lift for the heel, a plug coupled to the lift and secured in the socket, a stiffener plate disposed on the upper surface of the lift and adapted to engage the tread, and formations on the plate bearing against 85 the walls of the socket to prevent deflection or bending of the plate.

3. An attachment for heels provided with sockets leading from the tread, comprising a plug member and a lift member integrally 90 united, a stiffener plate provided with prongs embedded in the lift and itself disposed on the upper face of the lift, and prongs or lips punched from the plate and engaging the walls of the plug, the said 95 prongs or lips leaving openings in the plate for the passage of the material integrally uniting the plug and lift, there being a central opening in the plate for the passage 100 of a securing screw, and the lift member being provided with an outwardly tapering opening opposite the opening in the plate, for the purpose set forth.

4. An attachment for metallic and other heels, comprising a lift, a plug, and a stiffener member having a portion interposed between the lift and the tread of the heel, the lift and plug members being integrally 105 united through the stiffener member, and means for anchoring the stiffener to one of the first mentioned members.

5. An attachment for metallic heels provided with a tread socket, comprising a plug insertible into the socket, a lift, a stiffener plate disposed between the plug and the face of the lift adjacent the tread and extending sufficiently beyond the walls of the plug to engage the tread, the plug and lift being united to one another through 115 openings in the plate, means for securing the plate in position, and lips or equivalent formations leading from the plate adjacent the walls of the plug for engaging the corresponding walls of the socket when the attachment is applied to the heel.

6. An attachment for metallic and other heels, comprising a lift, a plug, and a stiffener member having a portion extending beyond the plug, said portion being adapted 125 to come between the lift and tread of the 130

heel when the attachment is applied to the heel, the lift and plug members being integrally united through the stiffener member.

- 5 7. An attachment for metallic and other heels, comprising a lift, a plug carried thereby, and a stiffener member having a portion disposed beyond the plug and extending over the lift a sufficient distance to

come between the lift and tread of the heel when in service.

In testimony whereof I affix my signature, in presence of two witnesses.

DAVID H. FINBERG.
